DETERGENTS CONTAINING IMIDAZOLINE LACTATES

Hyman W. Zussman and Robert L. Bernstein, Providence, R. I., assignors to Alrose Chemical Company, Cranston, R. I., a corporation of Rhode Island

No Drawing. Application December 23, 1949,
Serial No. 134 863

12 Claims. (Cl. 252—153)

This invention relates to surface active agents of the cation-active type, and more particularly to the lactate salts of certain substituted imidazolines. It also relates to surface active compositions for use in organic liquids.

The primary use of the lactate salt of the substituted imidazoline of the present invention is in the preparation of cleaning fluids, particularly for dry cleaning of garments and other textile fabrics. Although this is the primary commercial use, they can be employed with successful results in the cleaning of metals and other solid surfaces where an organic solvent is employed, to free them of films, coatings or deposits including grease, oil and attached extraneous solid matter etc.

The cation-active type surface active agents of the present invention have detergent and sludge dispersing properties and, because of which, when used in fuel oil and lubricants are effective in dispersing sludge and varnish deposits in engines.

In the dry cleaning of textiles, e. g. finished materials composed of cotton, wool, natural silk, cellulose esters, regenerated cellulose, "nylon" or other synthetic fibers or filaments, and mixtures of these recited fibers or filaments, it has been a common practice to employ a volatile organic solvent such as "Stoddard solvent,"¹ a poly-chlor hydrocarbon, benzene or white spirit in which is dissolved a soap, for instance potassium or triethanol ammonium oleate, and if desired water. And dry cleaning fluids which contain a quaternary ammonium salt, polyethylene glycol esters of fatty acids, poly-ethyleneoxide ethers of higher alcohols or phenols and ammonium salts of alkyl aryl sulfonates and other surface active agents have been utilized in dry cleaning and related branches of liquid detergency. Many of these aforesaid mentioned surface active agents are not, however, very effective in improving the removal of solid soil. Many of them do little more than permit the inclusion of water in the solvent, which is recognized as possessing two advantages: reducing the build-up of static electricity and increasing the removal of water-soluble stains in the cleaning processes.

¹ "Stoddard solvent" is described in a U. S. Bureau of Standards publication "Stoddard Solvent CS-3-40." It is designated as petroleum distillate with a flash point not lower than 100° F. when tested in the Tag closed heater. The distillation range when a sample is distilled in a certain specified apparatus is that not more than 50% shall be recovered in the receiver when the thermometer reads 350° F., and the end point of maximum distillation temperature shall not be higher than 410° F. 50 55

We have discovered that the lactate salts of substituted imidazolines of the type described below are surface active agents which when incorporated in organic solvents produce unusually effective liquid detergents. They surpassed such cationic-active types of surface active agents as fatty acid amides, aliphatic primary-, secondary-, and tertiary amines, quaternary ammonium compounds, oxazolines and other imidazolines when formed into corresponding dry cleaning detergents.

The lactate salt of imidazolines substituted in the 2-position by a saturated aliphatic hydrocarbon of seventeen carbon atoms, particularly by the alkyl group we have found possess very pronounced surface active properties. Where this substituent has less than seventeen (17) carbon atoms the effectiveness is less as a detergent in organic liquids. Salts other than the lactate, which were investigated, including the caprate, oleate, acetate, hydroxyacetate, gluconate and tartrate were far less effective than the lactate. The lactate salts of 2-heptadecyl imidazolines incorporated in very small quantities in the conventional solvents of the dry cleaning industry are unusually effective liquid detergents.

Its formula is:

It can be definitely asserted that the 2-position substituted imidazolines in the form of a lactate salt, the substituent of which is preferably an alkyl radical of seventeen carbon atoms, when incorporated in such volatile solvents as "Stoddard solvent," perchloroethylene, trichloroethylene or carbon tetrachloride, produced a cleaning fluid superior to either these respective solvents alone or to such solvents containing such other cationic agents as mentioned supra.

45 It has also been found that this type of imidazoline salt substituted also in the 1-position by such groups as hydroxylethyl, aminoethyl, benzyl and ethyl benzene was also effective when incorporated in the above mentioned conventional, volatile organic solvents. Of these substances, the lactate salt of 1-hydroxylethyl 2-heptadecyl imidazoline is preferred. Its formula
50 is:

The compounds of the present invention mentioned supra may be used as additives in any of the dry cleaning solvents commonly in use such as those mentioned by Brown in the Journal of the Society of Dyers and Colourists 1933, page 42. Since very small quantities of any of these substances is all that is usually necessary, the cleaning processes employing the same are economical. This does not preclude the use of larger quantities. The amount for optimum results can be determined for any one compound, solvent and textile goods by a few trials.

The preferred embodiment of this invention relates to detergent compositions which contain the lactate salt of 1-hydroxyethyl 2-heptadecyl imidazoline. In the dry cleaning processes the fluids would ordinarily be those conventionally employed and in the metal cleaning processes those customarily employed in that branch of detergency.

The effectiveness of this cationic surface active agent as relates to dirt removal from fabrics will be proven. The test employed was the measurement of reflectance of swatches of the soiled cellulose acetate fabric and the same soiled fabric cleaned by various dry cleaning fluids; a photovolt-reflectometer model 610 was used. This machine sends a beam of constant intensity of light against the swatch. The principle of operation is that a certain percentage of this light is reflected back and picked up by a photoelectric cell. With a perfect reflecting surface, the reflectance will be 100% or 100, leaving off the percentage. A perfectly black body will have a reflectance of zero percent, i.e. 0.

The swatches of soiled fabric were cleaned under identical conditions. The solvent in each cleaning operation in the table below was perchloroethylene and there were five tests in which 0.25% of the respective various surface active materials listed in this table was present in the solvent. The reflectance values for each appear in the table.

TABLE:

Nature of Fabric Treatment:	Reflectance:
Check, i. e. Soiled Fabric (no treatment).	6
Solvent alone.	19
Solvent "Naccolene": ¹	30
Solvent stearylamine.	32
Solvent Hydroxyethyl Oleamide.	33
Solvent "Span 80": ²	33
Solvent. 1-hydroxyethyl 2-heptadecyl imidazoline lactate.	53

¹"Naccolene" is a trade-mark product understood to be an ammonium salt of an alkyl aryl sulfonate.
²"Span 80" is sorbitan mono-oleate, an oily liquid of sp. gr. 1.00-1.05; M. P. 5-6; I-W.; s. all and s. oil.

From this table it is quite apparent that the reflectance of this imidazoline derivative solvent treated swatch is far in excess of any of the others, meaning that there is less residual dirt in the fabric. Comparable results have also been obtained employing "Stoddard solvent" instead of the perchloroethylene above, wherein such varied fabrics as rayon, wool and cotton have been subjected to this reflectance test, each demonstrating as in the table the superior soil removing capacity of this imidazoline derivative.

The powerful dispersing and suspending action of this imidazoline derivative in dry cleaning solvents has in a qualitative yet effective way been demonstrated as follows:

Two pieces of white cotton fabric were well marked with lipstick; one piece was put into a jar of pure solvent and the other into the same or-

ganic solvent containing the 2-heptadecyl imidazoline lactate. The first swatch was pink, whereas the other was white, after each had remained the same length of time in the solvent, been removed and permitted to dry.

The lactate salt of 2-heptadecyl imidazoline when dissolved in the conventional dry cleaning organic solvent will partially or completely loosen paint, lipstick, wax, pencil, butter, milk, ink, orange and hair dressing stains from garments, as well as loosen glue and other spots even when used without moisture. With moisture such solutions are more efficient in removing the more water-soluble stains, including perspiration. However, water solutions alone are never employed. A solution of the lactate salt of 2-heptadecyl imidazoline in "Stoddard solvent," perchloroethylene or other common organic volatile solvents, when used without moisture will not cause shrinkage or wrinkling. Such solutions will clean knitted, loosely woven and soft woolens without change in dimensions. They are excellent detergents for textile materials which tend to fade in cleaning such as draperies, and seat covers. As little as two or three ounces of this salt per hundred pounds of garments employed at concentrations in organic solvents of $\frac{1}{10}$ to $\frac{1}{4}$ of 1% or thereabouts will step up dirt removal capacity of petroleum solvent at least 25% and of "Stoddard solvent" approximately 40%.

2-heptadecyl imidazoline lactate and such 1-position substituted derivatives as the 1-hydroxyethyl have limited solubility in many of the organic solvents. They are, therefore, in practice somewhat difficult to incorporate in the conventional dry cleaning solvents. It has been found advantageous to liquefy these lactate salts, which are in their pure form waxy solids, by the addition of various oil-solubilizing polyalcohol esters of higher fatty acids, petroleum sulfonates and other oil-solubilizing surface active agents; at the same time these lactate salts are by this made miscible with the organic solvent. Many of these solubilizing agents also improve the water emulsifying action of the detergent. The aforesaid polyhydric esters can be those of glycerol, ethylene glycol, dipropylene glycol, propylene glycol, polyethylene glycol, etc.

While it has been noted that some of these oil-solubilizing agents, such as polyethylene glycol 200⁴ monolaurate, polyethyleneglycol 300⁵ monolaurate or polyethylene glycol 400⁶ monooleate have a detrimental effect on the detergency of the lactate salt of 1-hydroxyethyl 2-heptadecyl imidazoline, several other oil-solubilizing agents, while themselves rather poor dry cleaning detergents, exhibit a marked synergistic effect when mixed with this imidazoline salt. Thus, while 0.25% of dipropylene glycol monooleate increases the reflectance of standard rayon fabric from 11 to 21 in perchloroethylene, and a 0.25% solution of the lactate of 1-hydroxyethyl 2-heptadecyl imidazoline alone increases the reflectance to 45, a 0.25% solution of 1:1, 1:2 and 2:1 mixture of the former with the latter each produce reflectance of 43 to 47 employing the same solvent in each comparative test.

It may also be desirable to add small quantities of isopropanol, ethyleneglycol, "carbitols" i.e. diethyleneglycol-monoethyl ether, or hexylenglycols, etc. as coupling agents to improve the physical stability of the 2-heptadecyl imid-

⁴⁵⁶ The numbers 200, 300 and 400 mean that the polyethylene glycol from which these respective esters were made had the molecular weight corresponding to that number.

azoline lactate concentrates as articles of commerce. By "coupling agents" is meant a chemical substance which possesses the property of solubilizing or dispersing a compound that is normally only partially soluble in a solvent, which may be either an aqueous or a non-aqueous type. In the absence of the second additive this first substance would settle out of solution due to its limited solubility. The term "coupling agent" is broader than "oil-solubilizing agent" which is restricted to promoting solubility of the compound in the water-immiscible organic solvents.

The following examples are given to illustrate the invention but do not limit the invention. The parts are by weight.

Example 1

	Parts
Lactate salt of 1-hydroxyethyl 2-heptadecyl imidazoline	40
Dipropylene glycol mono-oleate	20
Glycerol mono-oleate	35
Ethylene glycol monobutyl ether	5

One quart per hundred pounds of garments of a dry stock solution prepared by thoroughly dispersing one part of the above material into ten parts of petroleum solvent will be found to increase the soil removal efficiency of petroleum solvent at least 40% while enabling complete or at least partial removal in the dry cleaning machine of such stains as lipstick, paint, and ink and at the same time will prevent soil redeposition.

Two quarts per hundred pounds of garments of a wet stock emulsion prepared by emulsifying one part of water with one part of the above dry stock solution will be found to increase the soil removal efficiency of petroleum solvent while removing such stains as coffee, fruit juices, gravy, etc. in the dry cleaning wheel in addition to removing the stains by the dry stock solution alone, as mentioned supra. As in the case of dry stock solution, soil redeposition is prevented.

Both the dry stock solution and the wet stock emulsion will increase the number of silk pass ups at least 50% and at the same time decrease the number of re-runs which are necessary. In addition, the wet stock emulsion will increase reversible pass ups 80% or better while keeping the amount of wet cleaning down to a maximum of 10%.

Example 2

	Parts
Lactate salt of 1-hydroxyethyl 2-heptadecyl imidazoline	30
"Nonisol" 200	25
Glycerol mono-oleate	40
Ethylene glycol monobutyl ether	5

Four fifths of a pint per 30 pounds of garments of a dry stock solution prepared by thoroughly dispersing one part of the above material into ten parts of synthetic solvent (trichlorethylene) it will be found to be at least double the soil removal efficiency of this solvent while enabling the complete or at least partial removal in the dry cleaning machine of such stains as lipstick, paint, and ink. At the same time the use of this dry stock solution will prevent soil redeposition.

One pint per 30 pounds of garments of a wet stock emulsion prepared by emulsifying four parts of water with eleven parts of this dry stock solution using chlorinated solvent will do all that the dry stock solution will do and, in addi-

tion, will remove such stains as coffee, paint, and ink plus the usual soft and sweet stains.

Both the dry stock and the wet stock emulsion will be found to increase the number of silk pass ups 65% while decreasing the number of re-runs necessary. In addition, the wet stock emulsion will increase reversible pass ups 80% or better and will keep the amount of wet cleaning needed to a maximum of 10%.

10 "Nonisol 200" is a trade-mark product of the non-ionic type of the Alrose Chemical Company, Cranston, Rhode Island.

Example 3

	Parts
Lactate salt of 2 heptadecyl imidazoline	20
Petroleum solvent	80

One quart of the above mixture per 100 pounds of garments will be found to increase the soil removal efficiency of petroleum solvent, prevent soil re-deposition, remove many stains not affected by the solvent alone and when used in conjunction with water will remove common water soluble stains.

25 One gallon of such formulations supra as exemplified (based upon the non-inclusion of the solvent) will ordinarily clean 4000 to 6000 lbs. of clothes. It can be added directly to the wheel. When employed in a dry condition, only one or two ounces per fifty pounds of clothes is sufficient. A stock solution may be prepared from 1 quart of the formulation from Examples 1, 2 or 3 and 20 quarts (5 gallons) of solvent. As a moisturized detergent one quart of one of 35 the formulations, 7 quarts of solvent and one quart of water is suggested. A ratio of 1.5 pints of this moisturized stock detergent solution per fifty pounds of garments (light or dark woolens, silks, whites) is usually ample to secure 40 excellent cleaning results. More moisture may be used as desired.

For prespotting, a higher ratio of the formulation to solvent is employed, such as one part of the formulation to 3-4 parts of solvent, with or without moisture emulsified in it; this makes a powerful prespotting preparation. Heavily moisturized prespotting preparations with such salts as these imidazoline derivatives therein may be used in cleaning plants employing carbon tetrachloride to derive the benefits of moisturized cleaning but without putting moisture into the dry cleaning machines.

Some of the advantages in employing lactate salts of imidazoline substituted in the 2-position by an alkyl group of seventeen carbon atoms will now be summarized. The flash point of the lactate salt of both the 2-heptadecyl imidazoline and the 1-hydroxyethyl 2-heptadecyl imidazoline is 235° C. It may be used with or without moisture as desired in organic solvent detergency, depending upon whether the presence or absence of moisture is the most efficient or whether water will cause shrinkage. It prevents soil re-deposition in dry cleaning. It secures an improvement in dry cleaning quality, reducing spotting and wet cleaning costs and giving better cleaned garments. Silk pass-ups⁷ in plants using it have doubled, and pass-ups on reversibles have been 80% and higher. In dry cleaning its use produces garments with a soft, fresh feel and the garments are easy to press and finish. More-

⁷ A pass-up is a garment which does not have to be put upon the spotter's board for further cleaning because of spots or stains. A reversible pass-up is understood as any garment usually made of cotton which is worn as a rain-coat or light overcoat.

over it leaves no odor upon the garments. Used with organic solvents it builds up no filter pressure on prolonged use. It may be used with any dry cleaning equipment and with any filter aid. And in the recovery of solvent it does not foam in the still. It is non-corrosive to metals and actually reduces the danger of corrosion when carbon tetrachloride is employed.

In cleaning solid surfaces higher boiling solvents may be used instead of these customarily employed in the dry cleaning industry. But the cationic-active surface active agents of the present invention may be employed with such organic liquids with similar effectiveness. In fact it finds service in organic liquid detergency in its many diverse industrial fields.

Moreover because of its surface active properties the lactate salts of the seventeen carbon atoms saturated aliphatic hydrocarbon, substituted imidazolines and the 1-position substituted derivatives of the type indicated herein also can be used to disperse sludge in fuel oil and lubricants.

While the invention has been described with reference to particular embodiments and specific examples, it is not intended that our invention shall be limited to such, except as hereinafter described in the appended claims. It will be realized by those skilled in the arts that various changes may be made in the composition and formulation of the detergents and cleaning agents.

We claim as our invention:

1. A surface active compound which is the lactate salt of the imidazoline substituted in the 2-position by an alkyl group of seventeen carbon atoms, but whose 4 and 5 positions are unsubstituted.
2. A surface active compound which is the lactate salt of the imidazoline substituted in the 2-position by an alkyl group of seventeen carbon atoms and in the 1-position by the hydroxyethyl group, but whose 4 and 5 positions are unsubstituted.
3. A surface active compound which is the lactate salt of 2-heptadecyl imidazoline.
4. A surface active compound which is the lactate salt of 1-hydroxyethyl 2-heptadecyl imidazoline.
5. A surface active compound which is the lactate salt of 2-heptadecyl imidazoline substituted in the 1-position by a member of the group consisting of hydroxyethyl, aminoethyl, benzyl and ethyl hexyl.
6. A surface active composition comprising the lactate salt of an imidazoline which is substituted in the 2-position by an alkyl group of seventeen carbon atoms and is substituted in the 1-position by the hydroxyethyl group, but whose 4 and 5 positions are unsubstituted, and a polyhydric alcohol ester of a higher fatty acid, this last mentioned component being present in an amount sufficient to liquify the former and render it miscible with the chosen liquid selected from the group consisting of hydrocarbons and polychlorinated hydrocarbons.
7. A surface active composition comprising a

lactate salt of an imidazoline which is substituted in the 2-position by an alkyl group of seventeen carbon atoms but whose 4 and 5 positions are unsubstituted, admixed with a dipropylene glycol ester of a higher fatty acid, the last component being present in an amount sufficient to liquefy the former and render it miscible with the chosen liquid solvent selected from the group consisting of hydrocarbons and polychlorinated hydrocarbons.

8. A surface active composition comprising the lactate salt of 2-heptadecyl imidazoline admixed with a dipropylene glycol ester of a higher fatty acid, the last component being present in an amount sufficient to liquefy the former and render it miscible with the chosen liquid solvent selected from the group consisting of hydrocarbons and polychlorinated hydrocarbons.

9. A surface active composition comprising the lactate salt of 1-hydroxyethyl 2-heptadecyl imidazoline lactate admixed with a dipropylene glycol ester of a higher fatty acid, the last component being present in an amount sufficient to liquefy the former and render it miscible with the chosen liquid solvent selected from the group consisting of hydrocarbons and polychlorinated hydrocarbons.

10. A liquid detergent comprising a volatile organic liquid solvent selected from the group consisting of hydrocarbons and polychlorinated hydrocarbons containing therein a lactate salt of an imidazoline which is substituted in the 2-position by an alkyl group of seventeen carbon atoms but whose 4 and 5 positions are unsubstituted, the said lactate salt of the imidazoline being present in the liquid detergent in an amount of not over a few per cent based on the concentration in the organic liquid solvent.

11. A liquid detergent comprising a volatile organic liquid solvent selected from the group consisting of hydrocarbons and polychlorinated hydrocarbons containing therein a lactate salt of an imidazoline which is substituted in the 2-position by an alkyl group of seventeen carbon atoms but whose 4 and 5 positions are unsubstituted and is substituted in the 1-position by a member of the group consisting of hydroxyethyl, aminoethyl, benzyl and ethyl hexyl, the said lactate salt of the imidazoline being present in the liquid detergent in an amount of not over a few per cent based on the concentration in the organic liquid solvent.

12. A surface active composition comprising the lactate salt of 1-hydroxyethyl 2-heptadecyl imidazoline and dipropylene glycol mono-oleate, the ratio of the former to the latter being 2:1-1:2.
